FIG - 1

FIG - 2

FIG. 1 is a perspective view of a tire showing my new design, it being understood that the design is repeated throughout the circumference of the tire as shown schematically by solid lines, the opposite side being substantially the same as that shown; and

FIG. 2 is a cross-sectional view taken on line 2—2 of FIG. 1.

I claim:

The ornamental design for a tire, substantially as shown and described.
